UNITED STATES PATENT OFFICE.

JOHN O. PETTEY, OF BELVIDERE, ILLINOIS.

SAW-SETTING MACHINE.

1,123,365.

Specification of Letters Patent.

Patented Jan. 5, 1915.

Application filed December 26, 1913. Serial No. 808,798.

To all whom it may concern:

Be it known that I, JOHN O. PETTEY, a citizen of the United States, residing at Belvidere, in the county of Boone and the 5 State of Illinois, have invented certain new and useful Improvements in Saw-Setting Machines, of which the following is a specification.

This invention relates to machines for setting the teeth of saws of various kinds.

The object of my invention is to provide an improved means for operating and controlling the action of the hammer or tool which is operable upon the teeth of a saw 15 for setting same; and further, to construct said means to be operable in an intermittent stroke action, whereby upon an operating stroke being made in one direction the said hammer will first be caused to strike the saw 20 tooth and then be moved to an inoperative position by the latter part of the movement of said operating stroke.

In the accompanying drawings: Figure 1 is a front elevational view of my improved 25 saw setting machine, shown in an inoperative position. Fig. 2 is a side elevational view of Fig. 1. Fig. 3 is a vertical sectional view through the machine as taken on the line 3—3 of Fig. 1. Fig. 4 is a plan sectional view as taken on the line 4—4 of 30 Fig. 3.

The body of the machine is adapted to be mounted upon a fixed support and is formed with a base 5 which serves as an anvil and 35 has a saw receiving face 6, a comparatively narrow back 7 which carries at its upper end a hollow column 8 whose axis is vertical and in alinement above the said anvil saw face, and an extended bearing 9 intermediate 40 ate the anvil and said column and having its axis in alinement with that of the column. A hammer 10 is mounted with its opposite end portions slidable lengthwise in the bearing 9 and column 8, the lower end of the 45 hammer having a tooth-set 11 and the upper portion having a tappet 12, the end of which is guided in a vertically extending slot 12'. A spiral spring 13 is located within the column, resting upon the top end of the hammer, and adjustable screw 14 received in the top of the column opening holds said spring tensionally depressed upon the hammer. A horizontal shaft 15 is mounted in the back 7 and extends from said 50 back to close proximity of the hammer 10. A toothed wheel 16 is mounted upon the

shaft 15 adjacent the hammer and each tooth is shaped with a peripheral face 17 upon which the tappet is adapted to rest, a dog engaging face 18 and an inclined face 19, the indents between the teeth being of such depth as to allow the tappet to be movable thereinto the depth of the hammer stroke. A lever 20 is pivoted intermediate its ends to the shaft 15, carries at one end 60 a pivoted dog 21 which is engageable with faces 18 of the wheel 16, and has a stop 22 at its dog end which is contactable with the body to limit downward movement of the said end at a point with the dog just having 65 engaged with a tooth face 18. A spring 23 is coiled about the bearing of shaft 15 and has an end 24 in engagement with the dog, holding the same yieldingly in engagement 70 with the toothed wheel and at the same time exerting a yielding downward pressure upon the dog end of lever 20, the stop 22 limiting movement of said end. Suitable 75 operating means may be connected to the end 25 of lever 20 to operate same intermittently.

In the operation of the saw setting machine a saw resting with its edge upon face 6 may be moved either by hand or otherwise to present new teeth to the set, as is 80 well understood in the art. With the movable parts in an inoperative position as shown in Fig. 1, that is, with the hammer held elevated by its tappet 12 being set upon tooth face 17 and the lever held with its dog 85 engaging a tooth face 18, the end 25 of the lever will be moved downwardly to set a tooth. At the commencing of such lever operation the wheel 16 will be moved rotatably by the dog and the tappet 12 released 90 allowing the hammer to be forced down by the spring 13 in a setting stroke which is limited by said tappet striking the bottom of the tooth indent, and upon continuing 95 said downward movement of the lever the rotation of the wheel 16 will cause the tappet to be raised by the inclined face 19 of the following tooth, to a position resting upon the face 17 of this tooth, whereupon the end of the dog will strike the tappet and limit 100 further movement of the lever in this direction (this position shown dotted in Fig. 1). The end 25 of the lever is then released by 105 the operator and it will move to its raised position by the action of spring 24, leaving 110 the hammer set in an elevated position ready for a succeeding stroke.

I claim as my invention:

1. In a device of the character set forth, the combination with a reciprocable tool and a toothed-wheel, of a member in connection with the tool and being associated with the profile face of said wheel for operating said tool according to the tooth profile, and operating means for rotating said wheel intermittently, each such rotary movement being a positively predetermined distance for causing a feed stroke of said tool and for retracting and positioning the tool set for a subsequent action of said operating means.
2. In a device of the character set forth, the combination with a reciprocable tool and a toothed-wheel, of a member in connection with the tool and being associated with the profile face of said wheel for operating said tool according to the tooth profile, and operating means for rotating said wheel, said means having an operating movement positively limited to the extent of rotating said wheel the equivalent distance of one full tooth, said member being, by such rotation, released from a set position to become operatively active and to be retracted and positioned in said set position.
3. In a machine of the character set forth, a reciprocable tool, a cam, a member guided upon the cam-face and being connected with the tool for governing movement of same, said member being held in a set position to maintain the tool in an elevated position and adapted by movement of the cam to release said member allowing operative action of said tool and to retract the tool and position it in said set position, and operable means for moving said cam, having its operating movement positively limited to the extent of moving the cam to guide the tool member from the set to set position above described.
4. In a machine of the character set forth, a reciprocable tool, a cam, a member guided upon the cam-face and being connected with the tool for governing movement of same, said member being held in a set position to maintain the tool in an elevated position,
- adapted by movement of the cam to release said member allowing operative action of said tool and to retract the tool and position it in said set position, means intermittently operable for operative action, said means being connected with said cam, and means for positively limiting the operative action of said means to move the cam a positive predetermined distance which will guide said tool member from the set to set position above described.
5. In a machine of the character set forth, a reciprocable tool, a toothed-wheel, a member connected with the tool and being guided by the profile of the wheel-teeth, an operable member, and a dog carried by said member and being in contact with the wheel tooth-face for imparting rotary motion to said wheel.
6. In a machine of the character set forth, a reciprocable tool, a toothed-wheel, a member connected with the tool and being guided by the profile of the wheel-teeth, an operable member, a dog carried by said member and being in contact with the wheel tooth-face for imparting rotary motion to said wheel, and stop means for limiting opposite directions of movement of said member.
7. In a machine of the character set forth, a reciprocable tool, a toothed-wheel, a member connected with the tool and being guided by the profile of the wheel-teeth, an operable member, a dog carried by said member and being in contact with the wheel tooth-face for imparting rotary motion to said wheel, stop means for limiting opposite directions of movement of said member, and a common spring means for holding the dog in contact with said wheel and said member against one of the stop means.

In testimony whereof I have hereunto set my hand in presence of two subscribing witnesses.

JOHN O. PETTEY.
